UNITED STATES PATENT OFFICE.

THOMAS H. THOMPSON, OF STARBUCK, MINNESOTA.

ADJUSTABLE RACK AND SHELF SUPPORT.

SPECIFICATION forming part of Letters Patent No. 785,449, dated March 21, 1905.

Application filed March 21, 1904. Serial No. 199,125.

To all whom it may concern:

Be it known that I, THOMAS H. THOMPSON, of Starbuck, Pope county, Minnesota, have invented certain new and useful Improvements 5 in Adjustable Racks and Shelf Supports, of which the following is a specification.

My invention relates to devices designed to be placed upon the wall of a room to support hooks for clothes or other purposes; and the 10 object of my invention is to provide a shelf or hook support that can be placed on the wall without breaking or marring in any way the plastering or woodwork.

A further object is to provide a hook and 15 shelf support which can be easily adjusted to fit different-sized spaces on the wall.

The invention consists generally in various constructions and combinations, all as herein-after described, and particularly pointed out 20 in the claims.

In the accompanying drawings, forming part of this specification, Figure 1 is a plan view of a rack or hanger support embodying my invention. Fig. 2 is a longitudinal sectional view of said support. Fig. 3 is a front view of one end of the support, showing a shelf arranged thereon. Fig. 4 is a transverse section on the line xx of Fig. 3. Fig. 5 is a view showing the device for use in supporting a hat-rack. Fig. 6 is a transverse section on the line yy of Fig. 5. Figs. 7 and 8 are front views of one end of the support, showing modified forms of hangers thereon. Figs. 9 and 10 are transverse sectional views of the 35 same.

In the drawings, 2 and 3 represent pipe-sections of suitable size having contiguous threaded ends 4 and 5, one being interiorly and the other exteriorly threaded to permit 40 telescoping of said ends and allow the adjustment of the sections 2 and 3 toward or from each other to vary the length of the device.

The outer end of the pipe-section 2 is open and adapted to receive a plug 6, fitting snugly 45 therein and mounted on a block 7, having a roughened or serrated outer face 8 to prevent its slipping on the surface with which it is in engagement. The outer end of the pipe-section 3 is threaded to receive a nut 9, having 50 a series of flat faces provided with holes 10,

into which a pin may be inserted for convenience in turning the nut, and a wrench may also be used on the nut, if preferred. A sleeve 11 is adapted to slip over the outer threaded end of the pipe-section 3 and slide thereon, 55 and said sleeve has a block provided with a serrated face corresponding to the one in the opposite end of the pipe 2 and for the same purpose. Both of these blocks, as shown clearly in Fig. 2, project beyond the pipes on 60 one side and are adapted to bear upon the edge of a door or window casing and against a wall or another casing that lies in a parallel plane with said first-named casing. The extensions on the blocks are of sufficient length 65 to bring the pipe-sections out away from the wall and allow the hooks or hangers to be placed thereon.

In setting up the device the pipe-sections 2 and 3 are adjusted with respect to one another until the device is of suitable length to fit within the desired space, when the nut is revolved and the sleeve 11 moved outwardly to clamp the serrated surfaces of the blocks against the wall or casing surface and form a 70 rigid substantial support for hangers or other articles placed thereon. 75

With this device it is not necessary to drive nails or screws into the wall and break the paper or plastering or in any way mar the 80 woodwork or finish of the house. It is easily and quickly placed on the wall and whenever desired can be removed and set up in another position without leaving unsightly marks that are incident to the use of the ordinary wall 85 hanger-support.

In Figs. 3 and 4 I have shown the device adapted for use to support a shelf, and for this purpose I provide a hanger 12, adapted to fit over the pipes and having at one end a depending flange 13, that bears upon the wall. A bend or loop 14 is provided in the opposite end of each hanger, the upper section of the loop having a hole 15 to receive the downwardly-turned end 16 of an arm 17, and the lower section of said loop has a recess 18, forming a socket for said downwardly-turned end. The outer ends of said arms are upwardly turned to prevent the shelf 19 from accidentally slipping off, though it can be readily removed at 90 95 100

any time and other devices substituted therefor.

In Figs. 5 and 6 I have shown another form of hanger, 20, secured to the pipe-section in any suitable way, as by pins 21, said hanger having depending coat-hooks 22 and outwardly-extending arms 23, that are preferably upwardly inclined and connected by wires 24, which, with said arms, form a neat substantial 10 hat-rack.

In Figs. 7 and 9 still another modified form of hanger is shown, consisting of a part 25, secured to the pipe-sections and having a hinged connection 26 with an arm 27, that is provided with a curved part 28, to extend under and follow the surface of the pipe-sections and prevent the arms from swinging down to a vertical position. This device forms a very substantial hanger and may be used for 15 articles such as heavy overcoats, &c.

In Figs. 8 and 10 a hanger 29 is shown secured to the pipe-sections by the pin device, as heretofore described, and having a socket 30 in its under side to receive a pin 31, upon which 20 the articles may be placed.

I claim as my invention—

1. A device of the class described comprising two telescoping pipe-sections, one having a threaded outer end, a sleeve loosely mounted 30 thereon, an adjusting-nut, and blocks mounted in the outer end of said sleeve and in the corresponding end of the opposite pipe-section and said blocks having surfaces that extend laterally with respect to said pipe-sections, for 35 the purpose specified.

2. A device of the class described comprising a tube, a fixed bearing-block at one end of said tube, a second bearing-block at the other end, a sleeve slidably mounted on said tube and 40 carrying said second bearing-block, and a lock-

nut having a threaded connection with said tube and engaging said sleeve.

3. In a device of the class described, a support and means for clamping it upon a wall between two parallel surfaces, hangers loosely 45 mounted on said support and having depending ends to bear upon the wall, arms mounted on the opposite ends of said hangers, and a shelf carried by said arms.

4. A device of the class described, comprising 50 a support, a bearing-block at one end thereof, the other end of said support being exteriorly threaded and provided with a locking-nut, a sleeve arranged to slide on the threaded end of said support and be engaged by said nut, 55 and a second bearing-block carried by said sleeve.

5. A device of the class described comprising 60 a support exteriorly threaded at one end and provided with a lock-nut and a bearing-surface, a sleeve slidably mounted on said threaded end and also provided with a bearing-surface, the inner end of said sleeve being engaged by said nut, and hangers carried by said support.

6. A device of the class described comprising 65 a support, a bearing-block at one end thereof, a second bearing-block at the other end of said support, a movable carrying means for said second block mounted on said support, and a lock-nut having a threaded connection with 70 said support and engaging said carrying means, substantially as described.

In witness whereof I have hereunto set my hand this 16th day of March, 1904.

THOMAS H. THOMPSON.

In presence of—

RICHARD PAUL,
M. HAGERTY.
